UNITED STATES PATENT OFFICE.

HENRY H. CUTLER, OF MILWAUKEE, WISCONSIN.

MAGNETIC CLUTCH.

No. 821,022.

Specification of Letters Patent.

Patented May 22, 1906.

Application filed August 5, 1903. Serial No. 168,389.

To all whom it may concern:

Be it known that I, HENRY H. CUTLER, a citizen of the United States, residing at Milwaukee, in the county of Milwaukee and State of Wisconsin, have invented a certain new and useful Improvement in Magnetic Clutches, of which the following is a full, clear, concise, and exact description, reference being had to the accompanying drawings, forming a part of this specification.

My invention relates to improvements in magnetic clutches.

In all magnetic clutches there exists a tendency for the armature member to remain in contact with the magnet member after the energizing-coil has been deenergized, owing to the residual magnetism in the members. As this is oftentimes objectionable, various schemes have been devised for separating the armature member from the magnet member on deenergizing the winding of the magnet member. In some instances a spring has been employed for this purpose.

In the present invention it is proposed to effect the separation of the armature member from the magnet member on deenergizing the clutch-winding by a supplemental winding employed only for the purpose of exerting a force to separate the clutch members and not to connect the same. Accordingly in the preferred embodiment of my invention I construct the clutch with a supplemental winding which may be energized to separate the members of the clutch from each other on the deenergization of the clutch-winding.

The preferred embodiment of my invention is illustrated in the accompanying drawings, in which—

Figure 1 is a sectional view of my improved clutch, and Fig. 2 is a diagram of the circuits.

Throughout the accompanying drawings like reference characters designate similar and corresponding parts.

The clutch shown in said drawings has a magnet member 1, which in the present instance has its periphery adapted for use as a pulley, and an armature member 2. The armature member is fixed upon the shaft 3, while the magnet member is free to rotate independently of said shaft and armature member.

The armature member is fastened to a flange upon the hub 4, which is of non-magnetic material, such as brass or other equivalent material, by screws 5, the hub being

fixed to the shaft 3 by a key 6. The magnet member is mounted to be rotatable upon the hub 4 and has its walls which bear upon said hub preferably provided with annular channels 7 for lubricating or packing rings.

The main winding 8 of the clutch for energizing the magnet to attract the armature member 2 to the magnet member 1 is arranged within an annular channel formed in the face of the magnet member opposite the armature member, a cover 9 being provided to protect said winding and hold the same in place. In the opposite side of the magnet member is another annular channel, in which is arranged a supplemental winding 10. An armature-plate 12 is situated adjacent to the side of the magnet member in which the supplemental winding is located, and when the supplemental winding is energized it is attracted to the magnet member, as will be hereinafter explained. This winding, like the main winding, is held in place and protected by a cover 11, fitted in the annular channel for said winding. The armature-plate 12 is loosely mounted upon the hub 4, so that it may revolve with the magnet member independently of the armature member of the clutch, and is connected with a ring 14 by one or more pins 13. These pins pass through suitable holes in the magnet member formed therefor, and the ring 14, which is preferably of brass or some other non-magnetic material, bears against the inner face of the armature member 2 and is preferably arranged in a depression in the face of the magnet member. The pins hold the armature member of the clutch and the armature-plate at such a distance from each other that when the magnet member is in contact with either the armature-plate or armature member it will be out of contact with the other.

In Fig. 2 is illustrated diagrammatically the circuits for the clutch. One terminal of each of the windings is connected by conductor 15 with the supply-main 17, the opposite terminals of said windings being connected by conductors 18 and 19 with separate points of a switch. The lever 20 of the switch is connected with the other supply-main 21 and when thrown to the right connects the primary winding 8 in circuit and when thrown to the left connects the supplemental winding 10 in circuit.

By the construction of the clutch herein shown the armature member may be quickly

192. CLUTCHES & POWER-STOP CONTROL

8.4

821,022

separated from the magnet member by connecting the supplemental winding in circuit after deenergizing the main winding. On energization of the supplemental winding the 5 primary or magnet member will be quickly separated from the secondary armature member by the former being attracted toward the armature-plate of the supplemental winding, the secondary member being held in a fixed 10 position by the pins which pass through the primary member.

Under certain conditions it might be desirable to have the supplemental winding energized constantly, or before the main winding is deenergized, so that on opening the circuit of the main winding of the clutch the separation of the members will take place almost instantaneously. To effect this result, the circuits for the windings and the 20 switch may be readily arranged by those skilled in the art.

It is a matter of little moment which is the driven and which is the driving member of the clutch, as this depends upon the circumstance 25 or the manner in which the clutch is to be applied. I refer to the members of the clutch as the "magnet" member and "armature" member merely for convenience in describing my invention, and therefore it will be understood that the windings may be differently arranged or carried by other parts if it should be deemed more advantageous to secure the best results, and the part operated by the force exerted by the supplemental winding 30 can be arranged in other ways and differently connected to cause the separation of the clutch members.

These several ways in which the embodiment of my invention herein set forth may 40 be modified are suggested to illustrate how the construction of the clutch which I claim may be widely varied and the same yet remain within the spirit or principle of my invention. There are many other changes in 45 the construction, arrangement, and combination of parts which I have not noted, but which fall within the scope of my invention, and therefore I do not limit myself to any structure of the clutch except as I particularly specify in the claims appended hereto.

The terminals of the main and supplemental windings will be connected in the usual and well-known manner with collecting-rings, the leads or connecting-wires extending between 55 the windings and the collecting-rings being provided in suitable channels or openings extending through the field-magnet and the shaft.

Having described my invention, what I 60 claim as new, and desire to secure by Letters Patent, is—

1. In a magnetic clutch, the combination with a driving and a driven member, of a main winding for exerting a force to connect said 65 members with each other, and a supplemen-

tal winding for exerting a magnetic force to disconnect said members said windings adapted to be energized one at a time.

2. In a magnetic clutch, the combination with a driving and a driven member, of a main winding for exerting a force to connect said driven member with said driving member, a supplemental winding, and means operated by the force exerted by said supplemental winding when it is energized to entirely separate said members said windings adapted to be energized one at a time. 75

3. In a magnetic clutch, the combination with a magnet member, of an armature member arranged upon one side of said magnet member, a main winding for exerting a force to attract said armature member to said magnet member, a part arranged upon the opposite side of said magnet member and movable independently of said armature member, 80 means for normally holding said part out of contact with said magnet member when said armature member is in contact with said magnet member, and a supplemental winding for exerting a force to attract said magnet member to said part, whereby the magnet member may be entirely separated from the armature member when desired. 85

4. In a magnetic clutch, the combination with a magnet member, of an armature member arranged upon one side of said magnet member, a main winding for exerting a force to connect said armature member with said magnet member, a part arranged upon the opposite side of said magnet member and rotatable independently of said armature member, one or more pins passing through said magnet member and holding said part out of contact with said magnet member when the latter is in engagement with the armature member, and a supplemental winding for exerting a force when energized to bring said part and magnet member toward each other to entirely separate the members of the clutch. 90 100

5. In a magnetic clutch, the combination with a driving member, of a driven member, a main winding for exerting a force to attract said driven member to said driving member, a part normally bearing against said driven member and adapted to rotate independently 110 of said driving member, and a supplemental winding for exerting a force when energized to operate said part to entirely separate the driving member from the driven member. 115

6. In a magnetic clutch, the combination with a driving member, of a driven member movable relatively to said driving member, a main winding for exerting a force to connect said driven member with said driving member, a supplemental winding, and a part rotatable independently of said driving member operated by the force exerted by said supplemental winding when energized to entirely separate said driven member from said driving member. 120 125 130

7. The combination with a magnet member, of an armature member, a main winding carried by said magnet member for exerting a force to connect said armature member therewith, a supplemental winding also carried by said magnet member, and a part rotatable independently of said armature member operated by the force exerted by said supplemental winding when energized to entirely 10 separate said armature member from said magnet member.

8. In a magnetic clutch, the combination with a driving member, of a driven member arranged upon one side thereof, a main winding for exerting a force to attract said driven member to said driving member, an armature arranged upon the opposite side of said driving member and rotatable independently of said armature member, one or more pins 15 passing through said driving member and bearing against the driven member to hold said armature out of contact with said driving member when the driven member is in engagement with said driving member, and 20 a supplemental winding for exerting a force to attract said armature to said driving member to entirely separate the driving member from the driven member.

9. In a magnetic clutch, the combination with a magnet member, of an armature member arranged on one side thereof, a main winding carried by said magnet member for exerting a force to connect said armature member with said magnet member, an armature arranged upon the opposite side of said magnet member and rotatable independently of said first-mentioned armature member, one or more pins passing through said magnet member and bearing against the armature member 30 to hold said armature out of contact with the magnet member when the armature member is in engagement therewith, and a supplemental winding also carried by said primary member for exerting a force to attract said armature to said magnet member and thereby 35 entirely disconnect said armature member from said magnet member.

10. In a magnetic clutch, the combination with a magnet member, of an armature member movable relatively thereto, a main wind-

ing for exerting a force to attract said armature member to said magnet member, a plate bearing against said armature member and movable freely thereof, an armature arranged upon the opposite side of said magnet member, one or more pins extending through said magnet member and connected with said plate to hold said armature out of engagement with said magnet member when the armature member is connected with said magnet member, and a supplemental winding for exerting a force to attract said armature to said magnet member and thereby entirely release the armature member from said magnet member.

11. In a magnetic clutch, the combination with a magnet member loosely mounted upon a suitable hub of an armature member fixed to said hub, a second armature also loosely mounted upon said hub and arranged upon the opposite side of said magnet member to said armature member, one or more pins extending through said magnet member and holding said second armature out of contact with said magnet member when the latter is connected with said first armature member, a main winding carried by said magnet member for exerting a force to attract said first armature member to said magnet member, and a supplemental winding also carried by said magnet member, for exerting a force to attract said magnet member to said second armature and thereby release said magnet member from said armature member.

12. In a magnetic clutch, the combination with a driving member, of a driven member, a main winding for exerting a force to attract said driven member to said driving member, a supplemental winding for exerting a force to separate said driven member from said driving member, and means for energizing said windings one at a time.

In witness whereof I have hereunto subscribed my name in the presence of two witnesses.

HENRY H. CUTLER.
